UNITED STATES PATENT OFFICE.

GUSTAV L. SCHOETTLER, OF STE. GENEVIEVE, MISSOURI.

PAPER-CUTTER.

1,059,572.

Specification of Letters Patent.

Patented Apr. 22, 1913.

Application filed May 22, 1912. Serial No. 698,912.

To all whom it may concern:

Be it known that I, GUSTAV L. SCHOETTLER, a citizen of the United States, residing at Ste. Genevieve, in the county of Ste. 5 Genevieve and State of Missouri, have invented a new and useful Improvement in Paper-Cutters, of which the following is a specification.

This invention relates to an attachment 10 adapted to be applied to the usual form of paper holding machine, having a cutting bar attached thereto, and the object of the invention is to cause an end portion of the paper to curl outwardly, thereby enabling a 15 corner of the paper to be readily grasped when an additional supply is to be drawn from the roll.

The invention consists of the novel features of construction hereinafter described, 20 pointed out in the claim and shown in the accompanying drawings, in which,

Figure 1 is a perspective view of a portion 25 of a paper holder with a roll of paper held therein and with my attachment in place. Fig. 2 is a longitudinal section taken through an end portion of the cutter bar, a portion of my device being shown in top plan. Fig. 3 is a front face view of my attachment. Fig. 4 is a section on the line 30 4—4 of Fig. 3.

In these drawings 1 represents the paper holding stand, 2 the cutter bar and 3 the roll of paper. My attachment consists of a bar 4 rigidly secured upon the outer face 35 of an end portion of the cutter bar 2 and projecting beyond the end of said bar. The projecting portion is bent at a right angle to said bar and is then bent back again upon itself, thus forming an open rectangular loop 5. A second bar 6 has an angled end portion 7 which extends within the loop 5 and is loosely connected thereto by means of a suitable bolt 8. The bar 6 is adapted to extend beneath the outer layer 40 or sheet of the roll of paper, and runs parallel to the inner face of the cutter bar. A transversely curved spring 9 is arranged 45 at right angles to the inner end portion

of the bar 6 and is riveted thereto, said spring having a curvature substantially that 50 of the roll of paper. Adjacent said spring the bar 6 carries a laterally extending outwardly angled lug 10. The paper when drawn from the roll passes over the bar 6 and spring 9 and over the lug 10, and beneath the cutter bar 2 which carries the bar 4. The spring 9 prevents spreading of the remainder of the roll, and the outwardly angled lug 10 causes a corner portion of the paper normally projecting below the cutter 60 bar to extend outwardly, as shown in Figs. 1, 2 and 4, thereby enabling said corner portion to be readily grasped for the purpose of drawing an additional supply of paper from the roll. This attachment can 65 be applied to any of the usual forms of paper holding devices and can be made for attachment to either the right or left hand end of the cutter bar.

In applying the invention to new devices 70 of this kind the bar 4 and the loop 5 may be formed integral with the cutter bar, by simply extending the length of the bar and bending one end into the proper shape to form said loop.

75 What I claim is:

A device of the kind described comprising in combination with a paper holding device, a cutter bar, a second bar parallel thereto, means for connecting the second 80 mentioned bar with an end of the cutter bar, a spring carried by and at right angles to the inner end portions of the second mentioned bar, and a laterally and outwardly extending lug arranged adjacent said 85 spring, the paper traveling over said second mentioned bar, spring and lug and beneath the cutter bar as the paper is drawn from the holder, said lug causing a projecting corner portion of the paper to normally extend outwardly.

GUSTAV L. SCHOETTLER.
